SLIDE FASTENER BRIEF CASE

Henry J. Guenther and George G. Guenther,
New York, N. Y.

Application June 16, 1949, Serial No. 99,382

3 Claims. (Cl. 150—42)

1

This invention relates to flap-closure type portable receptacles, including brief cases, pocketbooks, portfolios and the like, and which are commonly made of flexible material such as leather, imitation leather, fabric, rubberized fabric and similar materials. Such receptacles are usually relatively narrow in width but frequently are expansible to greater width for accommodating variations in thickness of content.

The general object of the invention is to provide a flap-closure type portable receptacle having a slide fastener for removably securing the closure flap to the body of the receptacle and which will not interfere with the ready opening and closing of the flap.

A further related object of the invention is to employ a slide fastener between the flap and body of a flap-closure type receptacle in an arrangement such that the slide is the only part of the slide fastener to be manipulated in order to permit free opening of the flap.

Another object of the invention is to provide a flap-closure receptacle of the expansible type with associated and cooperative slide fastener means for securing the closure flap and securing means for holding the receptacle against undesired expansion.

These and other objects and advantages of the invention will be apparent to persons skilled in the art from a consideration of the attached drawings and annexed specification illustrating and describing a preferred embodiment of the invention.

In the drawings:

Fig. 1 is a front perspective view of a device embodying the invention showing it in closed position;

Fig. 2 is a rear perspective view of the device of Fig. 1;

Fig. 3 is a front perspective view of the device in open position and with the flap-closure thrown back;

Fig. 4 is a top plan view of a portion of the device expanded relative to the showing in Fig. 2 and illustrating the means for preventing further undesired expansion thereof.

Referring now to the drawings the body 10 of the receptacle comprises front and rear walls 11 and 12, a bottom wall 13 and a top closure flap 14. The bottom wall 13 is preferably formed as a separate piece, secured to the front and rear walls in any suitable manner, as by stitching, and wide enough to permit expansion of the receptacle to the desired extent. The closure flap 14 is preferably formed integral with the

2

rear wall 12 and has an intermediate portion 15 adapted to cover the top of the receptacle in its expanded or contracted position and a terminal portion 16 extending outwardly over the upper edge of the front wall 11 and downwardly therefrom to a point intermediate its height. The terminal portion 16 is adapted to be releasably secured to an intermediate portion of the front wall 11, in a manner hereinafter described, to lock the receptacle in closed position.

The ends of the receptacle comprise bellows-type collapsible webs 17 secured to the inner side edge portion of the front and rear walls 11 and 12 in any suitable manner, as by stitching, and having secured between the folds thereof a plurality of partition members 18, preferably of relatively stiff material such as pressed fiber board or the like. As will be apparent the bellows-type collapsible webs 17 permit expansion of the receptacle from a minimum thickness dimension, as when empty, to a maximum thickness dimension, as when fully loaded.

In accordance with the present invention the closure flap 14 is releasably secured to the front wall 11, intermediate the height thereof, by a slide fastener 19 comprising interdigitating elements 20 and 21 and a slide 22. The interdigitating elements 20 are carried by a strip of suitable material 23 such as cloth or the like, in known manner, which is secured to the terminal edge portions 24 of the closure flap 14. The interdigitating elements 21 are likewise carried by a strip 25 which is secured to the front wall 11 of the receptacle intermediate the height thereof as shown in Figs. 1 and 3.

In a preferred form of construction the front wall 11 is formed of upper and lower sections 26 and 27 which overlap at 28 and are secured together along their overlapping portions as by stitching 29, with the strip 25 positioned and secured therebetween. When the slide 22 is in closed position as shown in Fig. 1 the interdigitating elements 20 and 21 are securely locked together thus securing the terminal edge 24 of the closure flap to the front wall 11 intermediate the height thereof and holding the closure flap 14 in place over the top and upper portion of the receptacle to close it.

At one side of the body portion 10 we provide 50 a bifurcated member 30 having leg portions 31 and 32 secured respectively to a terminal side edge portion of the closure flap 14, as at 33, and to an edge of the front wall 11 at the overlapping portions 28 of the upper and lower sections 26 and 27, as at 34. The bifurcated member 30

is preferably made of the same material as the body portion 10 and is of a length such that the closure flap 14 may be swung upwardly to open position as shown in Fig. 3 to allow full access to the interior of the receptacle through the top thereof.

In accordance with the present invention the bifurcated member 30 is designed to permit the flap 14 to be freely opened by manipulation of the slide 22 without disengagement thereof from the interdigitating elements 20 and 21 and for this purpose is provided with strips 35 and 36, secured thereto in any suitable manner, and carrying the interdigitating elements 37 and 38 which constitute continuations of the interdigitating elements 20 and 21. Thus by moving the slide 22 into the bifurcated member 30 the bifurcations thereof may be separated to permit the flap 14 to be opened to its full extent. To close the flap 14 it is merely necessary to move the slide 22 to the right until it reaches the position shown in Fig. 1.

The bifurcated member 30 is also designed to hold the receptacle against undesired expansion and for this purpose is provided with a socket 39 adapted for snap fastener engagement with a stud 40 secured to the rear wall 12. To provide for variations in thickness of the receptacle caused by variations in the contents thereof additional studs 40 may be provided as desired.

In closed position the slide 22 is disposed at the extreme right of the body portion 10 with the interdigitating elements 20, 21 and 37, 38 in locked engagement and the bifurcated member 30 disposed around the end of the body portion and secured to the rear wall 12 by the snap fastener elements 39 and 40. When it is desired to open the flap 14 the snap fastener elements 39 and 40 are disengaged and the slide 22 moved to the left into the bifurcated member 30. The flap may then be opened to the position shown in Fig. 3 permitting access to the interior of the receptacle.

Various modifications of the invention described and illustrated will most likely occur to those skilled in the art to which the invention relates and may be made without departing from the spirit of the invention, the scope of which is indicated in the attached claims.

We claim:

1. A portable receptacle having opposite side members and end members and having a top opening defined by upper edges of one of the side members and the end members, a flexible closure flap secured to the second side member adjacent the top opening and adapted, when closed, to overlie the top opening and lie in overlapping relation with the upper portion of the first side

member, said closure flap having a free longitudinal edge and free end edges, a flexible elongated bifurcated member having a free closed outer end and opposite leg portions secured at their open inner ends, one to one end of the closure flap adjacent the longitudinal edge thereof and the other to the corresponding end of the second side member at a point spaced downwardly from the top opening, said leg portions of the bifurcated member being free of connection with the adjacent end member and being of sufficient length that with spreading apart of said leg portions the closure flap can swing upwardly to open position, opposite coacting lines of slide fasteners, one of said lines being secured to the longitudinal edge of the closure flap and one leg portion of said bifurcated member and the other said line of fasteners being secured lengthwise of the second side member in downwardly spaced relation to the top opening and to the second leg portion of the bifurcated member, and a slide coactive with the lines of fasteners having fastener opening movement in the direction of the bifurcated member and to the closed outer end of said bifurcated member.

2. A portable receptacle according to claim 1 further including fastener means for detachably securing the closed outer end of the bifurcated member to the first side member and across the adjacent end member.

3. A portable receptacle according to claim 1 wherein the end members are of bellows type to adapt the receptacle to expand to different widths, and further including fastener means adapted to detachably and adjustably secure the closed end of the bifurcated member to the first side member in different positions lengthwise of the side member and across the adjacent one of said end members.
